DESIGN FOR A COMBINED ELECTRIC RAZOR AND LIGHTING MEANS

Robert V. Powell, Oakland, Calif.

Application January 21, 1938, Serial No. 74,457

Term of patent 7 years

To all whom it may concern:

Be it known that I, Robert V. Powell, a citizen of the United States of America, residing in Oakland, in the county of Alameda and State of California, have invented a new, original, and ornamental Design for a Combined Electric Razor and Lighting Means, of which the following is a specification, reference being had to the accompanying drawing, forming part thereof.

In the drawing;

Figure 1 is a side elevational view of a combined electric razor and lighting means showing my new design,

Figure 2 is a plan view of the design illustrated in Figure 1,

Figure 3 is an end view of the design illustrated in Figure 1, and

Figure 4 is a fragmentary detail view at one end of my design.

I claim:

The ornamental design for a combined electric razor and lighting means, as shown.

ROBERT V. POWELL.
